United States Patent Office

Des. 228,950
Patented Oct. 30, 1973

228,950

BIN DISCHARGER

Ronald J. Ricciardi, 108 Malcolm Ave.,
Garfield, N.J. 07026

Filed July 15, 1971, Ser. No. 163,132

Term of patent 14 years

Int. Cl. D15—99

U.S. Cl. D55—1 D

Fig. 1.

Fig. 2.

Fig. 3.

FIG. 1 is a perspective view of a bin discharger showing my new design;

FIG. 2 is a side elevational view of the bin discharger;

FIG. 3 is an end view of the bin discharger; and

FIG. 4 is a top plan view of my bin discharger.

I claim:

The ornamental design for a bin discharger, substantially as shown and described.
